UNITED STATES PATENT OFFICE.

EDWARD A. RYON, OF WELLSBORO, PENNSYLVANIA, ASSIGNOR TO FRED W. SIEMENS,
OF WELLSBORO, PENNSYLVANIA.

GLASS-GRINDING MACHINE.

1,373,835.

Specification of Letters Patent.

Patented Apr. 5, 1921.

Application filed June 19, 1919. Serial No. 305,362.

To all whom it may concern:

Be it known that I, EDWARD A. RYON, a citizen of the United States, and a resident of Wellsboro, county of Tioga, and State of Pennsylvania, have invented certain new and useful Improvements in Glass-Grinding Machines, of which the following is a specification, reference being had to the accompanying drawings, forming a part thereof.

10 My invention relates to glass grinding machines which are adapted to produce decorated or "cut" glass articles and has special reference to machines of the general character shown and described in my Patents Nos. 1,251,114 and 1,251,115 of December 25, 1917.

One object of my present invention is to provide a simple, durable and compact machine of the aforesaid character that shall 20 be adapted to operate automatically at a relatively high speed and that shall require only the service of a comparatively unskilled attendant.

Another object is to provide a reliable 25 clamping device that shall be susceptible of ready manipulation and shall hold the tumbler or other glass article on which the work is to be done, securely in position.

Another object of my invention is to provide in a machine of the aforesaid type, 30 simple and improved means for automatically changing the position of the glass between the cuts of the grinding wheel, which shall complete more than a single design 35 made up of a plurality of cuts, for each rotative movement of the holder about the spindle of the machine as an axis.

Other objects and advantages of my invention will be hereinafter set forth and in 40 order that my invention may be thoroughly understood I will now proceed to describe the same in the following specification, and then point out the novel features thereof in appended claims.

45 Referring to the drawings:

Figure 1 is a front elevation of a machine arranged and constructed in accordance with my invention and constituting an embodiment thereof.

50 A partial plan view of the grinding wheel including stops which determine the depth of each cut is shown in Fig. 2.

Figs. 3, 4, 5 and 6 are sectional elevations taken respectively on the lines 3-3, 4-4, 55 5-5 and 6-6 of Fig. 1.

Figs. 7 and 8 are detail views of the stop mechanism which is adapted to bring the machine to rest when a tumbler or other article is completely decorated.

Fig. 9 is a detail plan view showing the 60 operation of the release rod.

Fig. 10 is a sectional elevation, taken on the line 10-10 of Fig. 1.

Fig. 11 is a sectional detail showing the 65 support for the ratchet lever.

A sectional elevation of the driving shaft and clutch is shown in Fig. 12.

Figs. 13 and 14 are sectional elevations on the lines 13-19 and 14-14 of Fig. 12.

Fig. 15 is a sectional elevation showing 70 the work holder or clamp and its actuating mechanism on a larger scale.

Fig. 16 is a plan view of the part shown in Fig. 15, and

Figs. 17 and 18 are sectional plans taken 75 on the lines 17-17 and 18-18 of Fig. 15.

Frame and cutting wheel.

The frame of the machine comprises a base 20 to which is secured a main bracket 80 or head stock 21, and a wheel bracket 22 on which a grinding or cutting wheel 23 is supported in adjustable bearing blocks 24.

Mounted on the bracket 22 are a pair of stops 25 which extend close to the cutting 85 edge of the wheel and have their ends squared off into a single plane as indicated at 26, to engage the glass and limit the depth of the cut which is made in the work.

The wear of the wheel is compensated for 90 by adjusting the bearing blocks 24 which may be accomplished in any suitable manner as, for example, by adjusting screws 27.

Work holder.

95

Rotatively mounted in the head stock or bracket 21 is a spindle 28 which is adapted to be axially reciprocated as hereinafter explained and extends beyond the bracket in the direction of the cutting wheel, its axis 100 being preferably in the central plane of the wheel. The work holder, as clearly shown in Fig. 15, comprises an L-shaped bracket 29 having a hub 30 which is mounted on and secured to the extension of the 105 spindle. A shaft 31 is rotatably supported in the arm 32 of the bracket 29 with its axis perpendicular to the axis of the spindle. A plug 33 is secured to the shaft 31 and is adapted to fit into a tumbler or other article 110

to be decorated on the machine. A clamp 34 which is adapted to engage the edge of the glass is also mounted on the shaft 31. Furthermore, the glass is held in position 5 by means of a clamping screw 35 which is coaxial with the shaft 31 and is mounted in a pivotal arm 36. This arm is supported by the body of the bracket 29 and may be swung to one side to permit the glass to be 10 placed on the holder or removed therefrom. The clamp 34 comprises a block 37 having radial slots 38 in which clamping jaws 39 are disposed. The block has the general form of a circular disk and is peripherally 15 screw-threaded as indicated at 40, to co-operate with an internally-threaded clamping ring or nut 41.

The block 37 has an annular notch 42 and the clamping jaws 39 have the form 20 of ring segments except for radial lugs 43 which extend into the notches 38. The segmental jaws have conical surfaces 44 to co-operate with a correspondingly curved surface 45 of the clamping ring. The arrangement of parts is such that a tumbler or the like may be mounted on the block 33 and extend into the cylindrical opening provided by the jaw segments. By turning 25 the internally threaded ring or nut 41 the jaws are forced radially inward on account of the wedging action of the co-operating surfaces 44 and 45, and securely clamp the tumbler in position. Since the jaws are 30 symmetrically arranged and are concurrently actuated the glass is clamped in a coaxial position relative to the shaft 31 on which the plug 33 and the block 37 are mounted.

The arm or projection 32 of the L-shaped 40 bracket 29 has a yoke extension 46 which provides spaced bearings 47 for the shaft 31, a ratchet 48 and a pawl carrier 49 being interposed between the spaced bearings. The pawl carrier is pivotally mounted to 45 turn about the shaft 31 as an axis and a pawl 50 is pivoted thereon and is pressed against the notched edge of the ratchet 48 by a spring 51. A ratchet lock 52 is pivoted at 53 on the bottom of the arm 32 50 adjacent to the pawl carrier 49 so that a single member, as hereinafter explained, is adapted to release the lock and actuate the pawl. The pawl carrier and lock are respectively retracted by springs 54 and 55. 55 The ratchet 48 has a downwardly extending pin or lug 56 which is adapted to actuate a trip and stop the machine when the tumbler has turned through a complete revolution about the shaft 31 as an axis.

60 *Spindle.*

The spindle 28 is rotatively mounted in 65 bearings 57 and 58 provided in the head stock or bracket 21. It has secured to it a collar 59 slotted at 60, a toothed ratchet

61 which is adapted to co-operate with a pawl 62 as shown in Fig. 10, and a brake drum 63 with which a brake band 68 co-operates. A hub 64 of a pawl carrying arm 65 is interposed between the toothed 70 ratchet 61 and the brake drum 63. A sleeve 67 is splined to the spindle 28, is yieldingly spaced from the collar 59 by a spring 66, and has an annular groove 69 which is engaged by projections 70 of an actuating 75 lever 71.

The brake band 68 has an upwardly extending projection 72 which extends through a slot 73 in a yoke 74 of the bracket 21.

Driving shaft and actuating mechanism.

The actuating lever 71 is pivotally secured to an upwardly extending lug 75 of the bottom of the bracket 21 by means of a pivot pin 76. It is formed to provide a pair of side 85 rods or bars which extend on opposite sides of the spindle 28 and are connected by webs 77 and 78. A driving shaft 79 is rotatively mounted in the head stock 21 below the spindle and substantially in parallelism 90 therewith. It extends through the actuating lever 71 between the webs 77 and 78 as clearly shown in Fig. 5, and has an annular cam 80 affixed to it in the plane of the actuating lever. Depending from the web 77 of the actuating lever is a projection 81 which extends into the cam groove of the annular cam 80 so that as the driving shaft 79 is rotated, the actuating lever is oscillated about the pin 76 as an axis. As a 95 result a longitudinal or axial movement is imparted to the spindle 28.

The driving shaft is provided with a clutch pulley 82 which is so arranged that it may be released to stop the machine. The 105 clutch pulley 82 comprises a driving pulley or sheave 83 having a hub 84 rotatably mounted on the outer end of the driving shaft 79. The pulley is held in place by a pair of spaced collars 85 which are pinned or otherwise secured to the driving shaft, a cylindrical keyway 86 being cut partly in the shaft and partly in the collars to form 110 bearings for a semi-cylindrical key 87. The inner end of the key is bent at an angle to the axis of the shaft, as shown in Fig. 12, and has a spring 88 connected to it and tending to hold it in locking position in Fig. 14. The bore of the sheave hub 84 is provided with a plurality of recesses 89 which 115 are complementary to the key slot in the shaft and are adapted to be engaged by the semi-cylindrical key 87, provided the latter occupies the position shown in Figs. 12 and 13, in which it is held by the spring 88.

On the other hand, if the outwardly extending arm of the key 87 is engaged by a stop rod 90 for example, and is swung in opposition to the spring 88, the key will move to such position as to release the pulley 130

from the shaft. The action of the stop rod 90 will be hereinafter explained.

Affixed to the driving shaft 79 is a cam block or eccentric 91, the peripheral surface 5 of which is engaged by a link 92 universally pivoted at 93 as shown in Fig. 11. The link 92 is held against the cam surface by a spring 94 and is connected at its outer end to the pawl carrier 65. The parts 65 and 92 10 form a toggle joint and the action of the eccentric or cam 91 when the driving shaft is rotated, is such as to oscillate the pawl carrier 65 and advance the ratchet 61 step by step. It is by this means that the spindle 15 28 is rotatively advanced between cuts while the actuating lever 71 and the annular cam 80 are relied upon to effect the forward and back motion of the spindle which advances the work toward and from the cutting 20 wheel.

The brake band 68 prevents an overrunning or a backward movement of the spindle which might otherwise result from the action of the ratchet pawl 62 which of course 25 intermittently and successively engages the ratchet teeth.

The universal pivot 93 may be constructed in any suitable manner and as shown in Fig. 11, comprises a block 95 having a cylindrical stud projection 96 which is rotatively mounted in the bracket 21 and is held in place by a pin or set screw 97, the inner end of the set screw being arranged to engage an annular groove 98 in the stud projection. The outer end of the block 95 is slotted to form jaws which receive one end 30 of the link 92, the joint being completed by a pin 99.

Stop mechanism.

40 A bell crank lever 100 is pivotally mounted on the driving shaft 79 adjacent to the inner section of the head stock. As shown in Figs. 1 and 4, arm 101 of this lever extends upward adjacent to the spindle 28 and has a laterally extending pin 102 which is in position to engage the outer periphery of the collar 59 and enter the slot 60 when the spindle is at the outer end of its axial stroke 45 and the bell crank lever is released. The other arm 103 of the lever extends downwardly in position to be engaged by a hub 50 104, of a handle 105.

The handle 105 is secured to the release 55 rod 90 which is slidably mounted in the bracket 21 being loosely fitted into an opening 106 in the inner branch of the bracket as shown in Fig. 8. The rod is provided with a notch 107 which is adapted to be engaged by a stationary finger 108, which thus 60 serves to hold the rod at the outer extremity of its axial movement in opposition to a spring 109 which tends to move the rod to the opposite end of its travel determined by the

engagement of a collar 110 with the outer 65 section of the head stock (see Fig. 1).

A spring 111 presses the rod upwardly so that it is held in the top of the opening 106 except when it is released. This is effected by turning the rod through an angle sufficient to turn the slot 107 out of engagement with the finger 108. This turning may be done manually by grasping the handle 105 if desired, or it may be done automatically, as hereinafter explained, by the tripping 70 action of the pin 56 of the ratchet 48, upon a lateral arm or projection 112 which is adjustably secured to the outer end of the rod 90 by a set screw 113, as shown in Fig. 8.

The hub 104 of the handle 105 is provided with a cam surface 114 in order that the bell crank lever 101 may be swung into released position when the stop rod 90 is reset, the hub 104 being relied upon when the rod is set for holding the bell crank 80 lever 101 in released position.

When the stop rod 90 is released the hub 104 of the handle 105 is carried out of range of the arm 103 of the bell crank lever which is thus released so that the pin 102 engages 90 the slot 60 as soon as the slot comes into registering position.

A pair of adjustable pins or projections 115 and 116 are screw-threaded into and extend through the section of the bracket 21 95 which is adjacent to the cutting wheel. They are symmetrically spaced on opposite sides of the axis of the spindle 28 and extend into the path of movement of the ratchet lock 52 and the pawl carrier 49, the arrangement 100 of parts being such that with each complete revolution of the spindle the ratchet lock 52 is released and the pawl carrier actuated to advance the ratchet twice.

Operation.

105 The operation of the machine is as follows,—assuming that the parts occupy the positions in which they are shown in Fig. 1, if power is applied to the driving pulley 110 83 the driving shaft will be turned together with the annular cam 80 and the cam or eccentric 91. The cam or eccentric 91 actuates the links 92 and 65 so as to advance the spindle 28 to a predetermined position in 115 which it is securely held by the actuating brake band 68 as already explained. The annular cam now begins to act with the result that the lever 71 is oscillated and passes the spindle 28 toward the cutting wheel. 120

The cutting wheel is of course driven at a high rate of speed and the glass tumbler which is designated 120 is brought into contact with the cutting edge of the wheel so that a single cut is produced, its depth being 125 positively fixed by the stops 25.

As the rotation of the driving shaft continues the spindle is retracted and at the

same time the cam or eccentric 91 comes into position to again actuate the ratchet and rotatively advance the spindle.

Two cuts are thus produced at an angle 5 to each other and the spindle has advanced substantially 180 degrees. The ratchet lock 52 is now released by the engagement of these parts with the adjustable pin projection 115 and immediately thereafter the 10 ratchet is advanced by the movement of the pawl carrier 49 in opposition to the spring 54. The ratchet 48 is thus advanced one or more notches, the shaft 31 being correspondingly turned and the tumbler being rotated 15 through a relatively small arc to a new position in which a second series of cuts is to be produced.

By the repeated action of the annular cam and the spindle ratchet, another set of cuts 20 is produced. The glass and the work holder have now turned through substantially a complete revolution and the ratchet lock and the pawl carrier are actuated by coming into contact with the other stationary pin 25 projection 116.

This action is repeated until the tumbler or work has been turned to a complete revolution which is determined by the pin projection 56 of the ratchet 48. This pin in 30 a predetermined position corresponding to the completion of the revolution of the shaft 31, moves in a path which is intercepted by the adjustable arm 112 of the stop rod and as soon as the spindle is turned the stop pin 35 56 actuates the arm 112, turns the rod 90 so that it is released from the stationary finger 108 and is thrown backwardly by the spring 109.

The hub 104 is now out of engagement 40 with the arm 103 of the bell crank lever 100 which is thus released and the lateral pin 102 is forced into engagement with the collar 59 in a position to engage the slot 60 thereof, as soon as the slot moves into register with the pin. The engagement of the pin with the slot 60 positively locks the spindle and prevents its continued rotation. Furthermore, the stop rod 90 when released, moves outwardly until its outer extremity 50 is in the path of movement of the outwardly extending branch of the key 87. As soon as the key engages the stop rod it is turned in opposition to the spring 88 and releases the clutch, permitting the driving pulley to 55 run free on the shaft. The machine is thus not only brought to a stop but the spindle is definitely locked so that it will not move improperly when it is again actuated.

When the machine is brought to a stop 60 automatically as just explained, the tumbler is completely decorated and may be removed and replaced by a new blank.

To start the machine the rod 90 is moved by means of the handle 105 so as to be reset. 65 This action releases the clutch key which is

immediately set by the spring 88 and since the hub 104 of the release handle has a cam surface 114, the bell crank lever 100 is retracted and the pin 102 released from the slot 60.

The number of complete series of cuts produced on the glass will depend upon the number of teeth in the ratchet 48 and the setting of the adjustable pin projections 115 and 116.

The number of cuts for each design depends upon the shape of the cams, the annular cam 80, for example, being arranged double so that the spindle is advanced and retracted twice in each half revolution.

The design may be altered however, and more cuts made if desired, by modifying the cam and changing the ratchet 61.

Various structural modifications may be effected within the spirit and scope of my invention, and I intend that only such limitations be imposed as are indicated in the appended claims.

What I claim is:

1. A glass grinding machine comprising 90 a grinding wheel, a driving shaft, a pulley thereon, a clutch for coupling the pulley to the shaft, a spindle, a ratchet and pawl connection between the shaft and the spindle for rotatively advancing the spindle step by 95 step, an annular cam on the driving shaft, and a rocking lever actuated by the annular cam to move the spindle toward and from the cutting wheel.

2. A glass grinding machine comprising 100 a grinding wheel, a driving shaft, a pulley thereon, a clutch for coupling the pulley to the shaft, a spindle, a ratchet and pawl connection between the shaft and the spindle for rotatively advancing the spindle step by 105 step, an annular cam on the driving shaft, a rocking lever actuated by the annular cam to move the spindle toward and from the cutting wheel, a work holder affixed to the spindle near one end, and means dependent 110 upon the completion of a predetermined movement of the work on the work holder for releasing the clutch.

3. A glass grinding machine comprising 115 a grinding wheel, a driving shaft, a pulley thereon, a clutch for coupling the pulley to the shaft, a spindle, a ratchet and pawl connection between the shaft and the spindle for rotatively advancing the spindle step by 120 step, an annular cam on the driving shaft, a rocking lever actuated by the annular cam to move the spindle toward and from the cutting wheel, a work holder comprising a shaft at an angle to the spindle, means dependent upon the rotation of the work 125 holder about the spindle axis for advancing the work on said shaft step by step, and means dependent upon the completion of a predetermined rotative movement of the work holder shaft for releasing the clutch 130.

to disconnect the driving shaft from the pulley.

4. A glass grinding machine comprising a grinding wheel, a driving shaft, a pulley thereon, a clutch for coupling the pulley to the shaft, a spindle, a ratchet and pawl connection between the shaft and the spindle for rotatively advancing the spindle step by step, an annular cam on the driving shaft, 10 a rocking lever actuated by the annular cam to move the spindle toward and from the cutting wheel, a work holder comprising a bracket secured to the spindle near one end, a shaft rotatively mounted in the bracket 15 and extending at right angles to the axis of the spindle, a ratchet secured to the work holder shaft, a pawl carrier rotatable on said shaft, a pawl on the pawl carrier cooperating with the ratchet and a plurality of 20 relatively stationary projections in the path of the pawl carrier adapted to actuate the pawl and ratchet and rotate the work holder shaft step by step as the spindle is rotated.

5. A glass grinding machine comprising 25 a rotatable work holder having a work holder shaft at right angles to its axis of rotation, a slideable stop rod, a spring tending to hold the rod in one position, a latch adapted to hold the rod in another position 30 in opposition to the spring, and means dependent upon the rotative adjustment of the work holder shaft for releasing the rod.

6. A glass grinding machine comprising a driving shaft, a clutch pulley, a clutch releasing key, a spring tending to set the clutch, a stop rod adapted to actuate the clutch key in opposition to the spring in one position, means tending to throw the stop rod into said position, a latch for holding 40 the rod in opposition to said means, and means dependent upon the position of the work for releasing the rod.

7. A glass grinding machine comprising a driving shaft, a clutch pulley, a clutch releasing key, a spring tending to set the clutch, a stop rod adapted to actuate the clutch key in opposition to the spring in one position, means tending to throw the stop rod into said position, a latch for holding 50 the rod in opposition to said means, and means dependent upon the work for rotat- ing the rod, the stop rod being adapted to be released from the latch when rotated.

8. A glass grinding machine comprising 55 a supporting bracket, a spindle rotatably and slidably supported thereby, a brake band for preventing a free rotative movement of the spindle, a ratchet and pawl for rotatively actuating the spindle step by step, 60 means for moving the spindle longitudinally forward and back, a work holder secured to the spindle, and means for positively locking the spindle when released.

9. A glass grinding machine comprising 65 a supporting bracket, a spindle rotatably

and slidably supported thereby, a brake band for preventing a free rotative movement of the spindle, a ratchet and pawl for rotatively actuating the spindle step by step, 70 means for moving the spindle longitudinally forward and back, a work holder secured to the spindle, a locking lever for preventing rotation of the spindle, and a stop mechanism adapted to release the locking lever.

10. A glass grinding machine comprising 75 a supporting bracket, a spindle rotatably and slidably supported thereby, a brake band for preventing a free rotative movement of the spindle, a ratchet and pawl for rotatively actuating the spindle step by step, 80 means for moving the spindle longitudinally forward and back, a work holder secured to the spindle, a locking lever for preventing rotation of the spindle, a driving clutch, a stop mechanism adapted to release the 85 clutch, and a locking lever for the spindle adapted to be released when the stop mechanism is actuated.

11. A glass grinding machine comprising 90 a spindle adapted to be rotatively and ax- ially moved, a work holder attached to the spindle, a locking lever for positively pre- 95 venting rotation of the spindle, a driving clutch, a stop rod adapted to release the clutch in one position, and to retract the locking lever in its opposite position.

12. A glass grinding machine comprising 100 a spindle adapted to be rotatively and ax- ially moved, a work holder attached to the spindle, a locking lever for positively pre- 105 venting rotation of the spindle, a driving clutch, a stop rod adapted to release the clutch in one position and to retract the locking lever in its opposite position, and means dependent upon the work holder for 110 releasing the stop.

13. A glass grinding machine comprising 110 a spindle adapted to be rotatively and ax- ially moved, a work holder attached to the spindle, a locking lever for positively pre- 115 venting rotation of the spindle, a driving clutch having a laterally extending release key, a spring tending to set the clutch, a stop rod adapted to engage the key and re- lease the clutch in one position, a spring 120 tending to hold the rod in said position, a latch adapted to hold the rod in a retracted position, a cam on the rod adapted to re- lease the locking lever in the retracted position of the stop rod, and means dependent upon the work holder for releasing the stop rod.

14. A glass grinding machine comprising 125 a spindle adapted to be rotatively and ax- ially moved, a work holder attached to the spindle, a locking lever for positively pre- 130 venting rotation of the spindle, a driving clutch having a laterally extending release key, a spring tending to set the clutch, a stop rod adapted to engage the key and re-

- lease the clutch in one position, a spring tending to hold the rod in said position, a latch adapted to hold the rod in a retracted position, a cam on the rod adapted to release the locking lever in the retracted position of the stop rod, a laterally extending arm on the stop rod, and an actuating pin on the work holder adapted to engage the arm and release the stop rod when the work occupies a predetermined position on the holder.
15. A glass grinding machine comprising a grinding wheel, and a fixed rigid and non-yielding stop extending close to the cutting edge of the wheel and adapted to determine the depth of the cut.
16. A glass grinding machine comprising

a cutting wheel, a support on which the wheel is mounted, a pair of rigid non-yielding stop members secured to the support and extending close to the cutting edge of the wheel.

17. A glass grinding machine comprising a cutting wheel, a support on which the wheel is mounted, a pair of rigid non-yielding stop members secured to the support and extending close to the cutting edge of the wheel and having their outer surfaces finished in a single plane to determine the depth of the cut.

In witness whereof, I have hereunto set my hand this thirteenth day of June, 1919.

EDWARD A. RYON.
